INVENTOR

Louis Bernard Woeste.

UNITED STATES PATENT OFFICE.

LOUIS BERNARD WOESTE, OF CINCINNATI, OHIO, ASSIGNOR OF ONE-HALF TO WILLIAM A. STEPHENS, OF CINCINNATI, OHIO.

MYRIAD REFLECTOR.

Application filed November 24, 1924. Serial No. 751,854.

This invention relates to a device of the type disclosed in Patent No. 1,214,863 which was issued to Louis Bernard Woeste, upon Feb. 6, 1917. The character of myriad reflector herein disclosed is that of a sphere, yet any other geometrical form may be substituted therefor, which is preferably hollow and has its surface covered with a multitude of mirrors. The reflecting properties of the mirror facets are utilized to primary advantage when the myriad reflector is suspended from a ceiling, and secondarily when suspended from a wall of a dance hall, ball room, theatre, or auditorium, then rotated either vertically or horizontally, beams of light of one or various colors being thrown on the myriad reflector's facets from the floor or stage upwards or against the same from various parts of such room, hall, stage or auditorium, by electric spot lights or other means, and thus casting upon the participants and spectators a multitude of moving and varied color spots and creating a most pleasing result. The device for rotating the myriad reflector is preferably arranged by suspending it from a ceiling or beam thereof and imparting thereto a rotary motion upon its vertical axis, although it may be rotated about an axis located horizontally, either from a ceiling or wall by means of additional gearing, to obtain thereby different results. The vertical axis position of the myriad reflector may also be arranged for a swinging motion if desired.

In the present invention an object has been to produce a myriad reflector which embodies an improved construction, in which the many reflecting facets are mounted on the surface of the sphere in a more secure and substantial manner than heretofore.

A further object is to produce a more reliable device that will rotate any length of time and for the most advantageous display of the myriad reflector, which is compact, easily installed and cared for, and relatively easy of access and cheap to operate.

These and other objects are attained in the myriad reflector construction described in the following specification and illustrated in the accompanying drawings in which:

Fig. 1 is a view of a myriad reflector constructed in accordance with the provisions of the invention described herein, and showing two means of support.

Figs. 2 and 3 are detail views of construction features.

Fig. 4 is a plan view, partially in section, of a device for operating the myriad reflector.

Fig. 5 is a side elevation, upon a somewhat larger scale, of the device shown in Fig. 4, parts being shown in section.

Fig. 6 is a view illustrating the manner of use of the device shown in Figs. 4 and 5, attached to the ball shown in Figs. 1 to 3 inclusive.

In the spherical base 7 upon which the reflector facets 8 are applied, the material used is such as papier-mâché or other easily molded plastic. The surface of this base is covered, in as closely spaced relation as possible, with a multitude of mirrors of relatively small dimensions and preferably of glass. Although the mirrors have been shown as circular in form, any other geometrical shape may be employed. It has been found that a simple manner of attaching these mirrors to the surface of the sphere, is to mount each of them first upon a base of metal, such as the plate 9, shown in Fig. 3. This is accomplished by placing the mirrors on the surface of the plates as shown, and then bending the diagonally opposite corners 10 of the plates over and into clamping engagement with the mirror, leaving the remaining diagonally opposite corners 11 free for the passage therethrough of nails or screws 12 through apertures 13 therein, and into base 7. The surface of the base is thus covered, as closely as possible, with these facets. The surface of the base thus presents a condition in which the intervening spaces between adjacent mirrors may be filled with a non-reflecting cementitious material 14 to present the relatively smooth and pleasing appearance which is somewhat as has been attempted for illustration in Fig. 1. In order to mount on high the myriad reflector for display purposes, a ring or other supporting element 15 may be located as shown in Figs. 1 and 6, for rotation upon a vertical axis, or a shaft may be provided in a horizontal plane for horizontal rotation as shown in Fig. 1.

In Figs. 4 to 6 has been shown a typical mechanism for the purpose of rotating the myriad reflector. This mechanism is mounted upon a platform 16' which is supported by means of chain 17', a ring 18

and eyes 19, from the ceiling. Centrally of this platform a shaft 20, is rotatively mounted and is provided with a hook 21 for engaging the ring 15. This shaft extends upwardly through a bearing 22 in a casing 23 which is held stationary relatively to the platform 16. The upper end of this shaft 20 is provided with a driving gear 24 which meshes with a worm 25 on a transversely extending intermediate shaft 26 mounted in the casing. This worm is driven by a gear 27 on the shaft 26. Meshing in turn with gear 27 is a worm 28 on the drive shaft 29 which is driven by the motor 30. A motor speed controller 31 is mounted on the platform to enable the speed of rotation of the myriad reflector sphere to be varied. Thus a relatively light compact and readily controlled reflector rotating device has been provided, in which a high speed electric motor has been provided bringing about a relatively slow and desirable speed of rotation of the myriad reflector.

Having thus described the invention what I claim is:

A myriad reflector of any geometrical form adapted to be rotated upon a substantially vertical axis, consisting of a base of desired shape, a series of facet holding plates fastened to the base and a light reflecting facet secured to each plate, each plate consisting of a piece of metal of substantially rectangular shape having diagonally opposite corners secured to the base, each facet being of substantially circular shape and having the diagonally opposite free corners of its mounting plate bent over into retaining relation to its face, and a cementitious non-reflecting material occupying the spaces between adjacent mounted facets on the base to cover the assembly with the exception of facet faces and turned over corners of the mounting plates.

In witness whereof, I affix my signature.

LOUIS BERNARD WOESTE.
